(57) **CLAIM**

The ornamental design for an cover for an electronic device as shown and described.

DESCRIPTION

FIG. 1 is a top, front perspective view of a cover for an electronic device, showing our new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof;

FIG. 7 is a bottom plan view thereof;

FIG. 8 is an enlarged view of the portion labelled 8 in FIG. 2;

FIG. 9 is an enlarged view of the portion labelled 9 in FIG. 5; and,

FIG. 10 is an enlarged view of the portion labelled 10 in FIG. 5.

Dotted broken lines illustrate environmental subject matter and form no part of the claimed design.
